UNITED STATES PATENT OFFICE.

HARRY KONERMAN, OF NEWPORT, KENTUCKY, ASSIGNOR TO THE GLOBE REGISTER COMPANY, OF CINCINNATI, OHIO, A CORPORATION.

AUTOGRAPHIC REGISTER.

SPECIFICATION forming part of Letters Patent No. 729,943, dated June 2, 1903.

Application filed June 9, 1902. Serial No. 110,775. (No model.)

To all whom it may concern:

Be it known that I, HARRY KONERMAN, a citizen of the United States, residing at Newport, in the county of Kenton and State of Kentucky, have invented certain new and useful Improvements in Autographic Registers, of which the following is a specification.

My invention relates to an autographic register, and has for its principal object the production of a simple and efficient summarizer. The slip ordinarily employed in registers has a figure-column at the right for the items of a purchase and the bottom line devoted to the total. With my invention the third roll or record-slip only contains these totals. This saves paper, gives the recording-compartment a much greater capacity, and is much easier to figure up when the sales-records are computed than where the whole section of strip containing the several items is recorded.

The features of my invention are more fully set forth in the description of the accompanying drawings, forming a part of this specification, in which—

Figure 1 is a top plan view of a register with my invention applied. Fig. 2 is a central vertical section of such a register. Fig. 3 is a detailed view, partly in section, of the summarizing device. Fig. 4 is a top plan view of Fig. 3. Fig. 5 is a detailed view, partly in section, of the actuating-gears for the delivery mechanism.

A represents the register-frame having the three rows of paper 1 2 3 journaled therein, as usual. The strips 1 2 3 pass over rolls a b c onto the writing-table B under the covering-plate C, with its writing-orifice D. The strips 1 2 pass thence between the clamping members of the reciprocating carriage E. The usual carbons are placed between the strips 1 2 3 on the writing-table in a suitable manner. The strips 1 2 are clamped by the carriage E and moved forward on delivery-table F the length of the slots f g h, the handle i of the carriage being then tilted back, the carriage brought back to initial position (shown in Fig. 2) and strips 1 2 torn off, the carriage riding on ways or guides on the delivery-table.

So far the mechanism is substantially the same as that shown and described in Letters Patent of the United States No. 566,620, issued

to Williard B. Preston on the 25th day of August, 1896, for autographic registers.

j represents an index finger or strip spanning the writing-orifice D, (see Fig. 1,) the smaller space being the place for writing in the totals on the strips. The carriage E is provided on one side with a tripping lug or dog k, extended down into slot h in the top of the delivery-table.

G represents a rack-bar having slots l m at opposite ends engaging over screws n o on the inside of the register-frame under the writing-table on the side upon which the dog k is depended. These slots and screws form ways on which the rack-bar G is reciprocated. The inner end of bar G is upturned, forming a stop against which the lug k engages in the return travel of carriage E, bringing the rack-bar back to first position. (Shown in Fig. 2.)

H represents a catch pivoted to the rack-bar G, having spring p to hold the inner end normally upturned, as shown in Fig. 3, in the path of travel of lug k. Slots l m are in the same horizontal plane; but the inner slot m has an upward inclination at its inner extremity. (See Fig. 3.) When the carriage is moved forward, lug k engages upturned end of the catch H, moving bar G forward until the upward incline of slot m travels over screw n, which allows this end of the bar G to drop, the upturned end of catch H being thus removed from the path of travel of the lug k. On the rearward stroke of the carriage the lug k passes over the catch H and strikes a stop-lug g on the rear end of the bar G, returning the latch to its initial position. Thus it will be seen that the rack-bar G only travels with the carriage E the distance represented by the length of the slot m. The writing-table B has a slot r (see Fig. 2) just beyond the end of the total-space formed by the partition-strip j, through which slot the third or record strip 3 is passed. From thence it is passed across the top of the interior of the register over roller s, journaled in the top of the register over the storing-compartment I. From thence it passes downward between delivery-rolls J K into the storing-compartment. Delivery-roll J is journaled in the frame and is actuated by mechanism to be next described.

The delivery-roll K is journaled in the ends

of arms L', pivoted at t to the frame of the machine and held by spring u in frictional engagement with delivery-roll J. v represents the rack-teeth on bar G.

5 L M represent, respectively, loose and fixed ratchet and gear wheels on the end of roll J, the rack-teeth v of bar G engaging the teeth of loose gear-wheel L. Between gear and ratchet wheels L M is a radius-bar N, pinned 10 to said gear L by pins w w, (see Fig. 5,) and from the end of said radius-bar depends a pawl O, held by spring P in engagement with the teeth of ratchet-wheel M in such manner that said wheel M is locked to turn with the 15 radius-bar in one direction of rotation and that the pawl slides idly over the teeth of said wheel M in the other direction of rotation. It is apparent, therefore, that as rack-bar G is moved forward it turns wheels L M in that 20 direction and delivers the record-strip into the storing-compartment, the pawl releasing the wheel M on the return stroke of bar G. Thus the record-strip is fed to the storing-compartment in step movements in lengths 25 which may be equal to the length simply required for writing in totals.

Having described my invention, I claim—

1. In an autographic register, a delivery-table, a sliding carriage thereon, a lug dependent from said carriage through a slot in the table, a pair of delivery-rolls under the table, a reciprocating bar mounted in guides under the table, rack and gear devices between the said bar and rolls, said rolls being fast in the 30 direction of delivery and loose in the reverse direction and lugs on the said bar adapted to be engaged by the lug on the carriage in the forward and rearward travel thereof, substantially as described.

40 2. In an autographic register, a reciprocating bar, a reciprocating carriage adapted to actuate said bar, a pair of delivery-rolls, a loose gear and a fixed ratchet-wheel on the end of one of said rolls, rack-teeth on the said 45 bar engaging the said gear, a pawl pivoted to said gear-wheel having its free end engaging with said ratchet and intermeshing gear-wheels fixed to the other ends of said rolls whereby the said rolls are positively 50 driven in one direction of the movement of the carriage and stationary during the return movement of the carriage, substantially as described.

55 3. In an autographic register, a delivery-table, a sliding carriage thereon, a pair of delivery-rolls under the table, a reciprocating bar mounted in guides under the table, rack and gear devices between the said bar and rolls, said rolls being fixed to said gear mechanism in the direction of delivery and loose 60 in the reverse direction, and interlocking devices between the said bar and carriage adapted to be engaged during the forward and rearward travel of the carriage, substantially 65 as described.

4. In an autographic register, a delivery-table, a sliding carriage thereon, a pair of de-

livery-rolls under the table, a reciprocating bar mounted in guides under the table, rack and gear devices between the said bar and rolls, said rolls being fixed to said gear mechanism in the direction of delivery and loose in the reverse direction, and interlocking devices between the said bar and carriage adapted to be engaged during the forward and rearward travel of the carriage, and means for disengaging said interlocking devices at a point intermediate of the forward travel of the carriage, substantially as described. 70 75

5. In an autographic register, a reciprocating bar, a reciprocating carriage adapted to actuate the same, a pair of delivery-rolls, a pair of arms pivoted to the frame in the free ends of which one of said rolls is journaled, the opposing roll having a fixed journal, a spring pressing the pivoted roll into yielding contact with the fixed roll forming a frictional drive, rack, ratchet, gear and pawl devices between the ends of one of said rolls and the said reciprocating bar adapted to drive said 80 rolls positively in one direction of travel of the carriage only, substantially as described. 85 90

6. In an autographic register, a reciprocating mechanism for discharging the detachable strip, a pair of delivery-rolls, a ratchet-wheel 95 fixed to one of said rolls, a gear-wheel loose on said roll, a radius-bar fixed to said loose gear-wheel, a pawl pivoted from said bar, means for holding said pawl in locking engagement with the teeth of the pawl-wheel in 100 one direction of rotation, a rack-bar engaging the teeth of said gear-wheel, a lug depending from the reciprocating mechanism, lugs on said bar against which said lug of the reciprocating mechanism engages in opposite 105 directions of movement, ways on which said bar travels, and means for depressing one of said lugs from the path of travel of said lug intermediate of the travel of the reciprocating mechanism, substantially as described. 110

7. In an autographic register, a reciprocating mechanism for discharging the detachable strip, a pair of delivery-rolls, between which passes the record-strip, a table over which travels said strip having an intermediate slot 115 for the escape of the record-strip, a ratchet-wheel fixed to one of said rolls, a gear-wheel loose on said roll, means fixed to said gear-wheel adapted to engage the ratchet-wheel in locking relation in one direction of rotation, 120 a rack-bar engaging said gear-wheel, a dog depending from said reciprocating mechanism, lugs projected from said rack-bar in the path of travel of said dog, and means for removing one of said lugs from the path of 125 travel of said dog intermediate of the travel thereof, substantially as described.

In testimony whereof I have hereunto set my hand.

HARRY KONERMAN.
